CLAIM

The ornamental design for a chimney cleaning device, as shown and described.

DESCRIPTION

FIG. 1 is a perspective view of a chimney cleaning device showing my new design;

FIG. 2 is a side elevational view thereof, the opposite side being a mirror image and shown with the brush retracted into the body of the cleaning device;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a bottom perspective view thereof as shown in FIG. 1; and,

The crosshatched pattern is partially shown for ease of illustration and is understood to repeat throughout the areas indicated.

FIG. 2

FIG. 3

FIG.4

FIG. 5

FIG.6

FIG. 7
